DESIGN.

—o—
J. L. FOLSOM.

CARPET.

No. 18,231.

Patented Apr. 3, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,231, dated April 3, 1888.

Application filed January 26, 1888. Serial No. 262,063. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of the figures A, B, C, and D, disposed, as shown, upon a ground of net-work ornamented with small geometrical forms.

20 Figure A has at one part a large circular geometrical form, from the edges of which extend small block-work projections or cross-shaped forms. This large circular form is ornamented with small geometrical figures, 25 and is separated from the rest of the entire figure by a Grecian border-work. The rest of the figure A is composed of small circular forms of a somewhat similar character closely massed and having a block-work border or outline of 30 an irregular form.

Figure B has at one part a large circular geometrical form, with conventionalized leaf forms at the center surrounded by geometrical ornamentation and block-work. From the 35 sides of this form extend block-shaped projections. This large circular part is separated from the rest of the figure by a Grecian border-work. The rest of the figure consists of a group of geometrical flower and leaf forms

having a block-work border more or less regularly indented. 40

Figure C has at one part a large circular geometrical form, consisting of crossed bars or bands ornamented with small geometrical figures, and having block-shaped arms projecting from its circumference. This large form is separated from the rest of the figure by a Grecian border-work. The other part of the figure consists of a group of square or diamond shaped geometrical forms having a very 45 irregular block-work border.

Figure D has at one part a large circular geometrical form, consisting of radiating bars or bands ornamented with small geometrical figures, and having at its center a smaller 55 circular figure similar to itself. This large form is separated from the other part of the figure by a Grecian border-work. The rest of the figure is made up of square geometrical forms arranged in a continuous body having 60 an irregular block-work border.

These figures are arranged upon a ground of irregular net-like work. In the spaces formed by this net-like work are a number of blocks resembling crosses and other small geo- 65 metrical forms.

What I claim as new, and desire to secure by Letters Patent, is—

1. The design for carpets, consisting of the figure C, substantially as shown.
2. The design for carpets, consisting of the figures A, B, C, and D and the ground-work, substantially as shown.

JAS. L. FOLSOM.
